UNITED STATES PATENT OFFICE.

FRANCIS L. COWAN, OF ARGENTA, ARKANSAS, ASSIGNOR OF ONE-HALF
TO THOMAS JEFFERSON BAILEY, OF ARGENTA, ARKANSAS.

GIN-BREAST.

SPECIFICATION forming part of Letters Patent No. 777,080, dated December 13, 1904.

Application filed December 24, 1903. Serial No. 186,455. (No model.)

To all whom it may concern:

Be it known that I, FRANCIS L. COWAN, a citizen of the United States, residing at Argenta, in the county of Pulaski and State of Arkansas, have invented a new and useful Gin-Breast, of which the following is a specification.

This invention relates to certain new and useful improvements in cotton-gins; and it has particular reference to an improved construction of the breast-board or, as it is sometimes called, the "roll-board."

The invention has for its object to provide a roll-board composed of a plurality of independent sections or members pivotally mounted upon a shaft or axis and spring-pressed at their free ends, the object being to permit the free ends of said individual members or fingers to yield to the pressure of the cotton roll when the cotton is fed so fast as to make said roll of larger size than normal. These individual spring-actuated members or fingers are disposed in alignment with the gin-saws in order that the said spring-actuated members or fingers may yield at the point or points where the pressure is greatest, thus compensating for any unevenness that may exist in the size of the roll throughout the length of the latter.

With these ends in view the invention consists in the improved construction and novel arrangement of conventional parts, which will be hereinafter fully described, and particularly pointed out in the claims.

In the accompanying drawings, Figure 1 is a vertical longitudinal sectional view of the front portion of a gin equipped with my improved roll-board. Fig. 2 is a transverse sectional view taken on the line 2 2 in Fig. 1.

Corresponding parts in both figures are indicated by similar numerals of reference.

1 designates a gin-casing of ordinary construction the sides of which are provided with bearings for the shaft 2, carrying the gin-saws 3. As no improvement in the gin beyond the breast-board or roll-board is claimed, other parts, such as the cleaner-brush and the mote-board, have been omitted from the drawings.

4 designates the feed opening or hopper,

through which the cotton is fed into the gin-chamber or roll-chamber.

A gin-breast of ordinary construction is indicated at 5.

My present improvement includes a front wall 7 and a pair of side pieces 8 8, which have extensions or ears 9, adapted to be connected exteriorly with the gin-casing, thus enabling the improvement to be applied to gins of ordinary construction without dismantling the same further than to remove the forward end of the casing. Between the side pieces 8 8, between the lower ends thereof, is mounted a cross-piece 10, and the said side pieces likewise have upward extensions 11, the rear edges of which are connected by a cross-piece 12, which latter abuts upon the front wall of the hopper 4. The side pieces 8 8 support near their lower ends a rod or shaft 13, upon which a plurality of fingers 14 are pivotally mounted. Said fingers are provided at their lower ends with sockets 15, in which are seated springs 16, normally bearing against the cross-piece 10 of the casing. The upper ends of the fingers are provided with recesses 17, forming lips 18, which normally abut upon the cross-piece 12, against which the upper end of the fingers are forced by the action of the springs 16 against the cross-piece 10 at the lower end of the casing.

As far as the construction of the fingers which coöperate to form the breast-board or roll-board is concerned it may be said that their working faces are to be properly curved to cause the roll to be properly formed; also, that the said fingers are fitted closely together—that is, as closely as may be without interfering with the free individual movement of each one of the fingers independently of the others. When in operation cotton is fed too rapidly into the gin, the fingers 14 will recede, so as to accommodate the roll without overtaxing and choking the saws. As soon as this condition is relieved the fingers, by the action of the springs 16, will be restored automatically to normal position.

I have in the foregoing described the fingers constituting the roll member as being pivoted at or near their lower ends; but I desire

- it to be understood that under some circumstances the conditions may be reversed and the pivotal points of the fingers be at or near the upper ends of the latter. This and other 5 modifications will be governed according to the construction of the gin to which my invention is applied. My invention, it will be further understood, may be applied to practically all gins when first constructed, or it may 10 be in the nature of an appliance to be attached to various gins by simply removing the front ends of their casings. In either case it is evident that changes as to shape, proportion, and general method of assembling the parts may 15 be resorted to for adapting the invention to the peculiarities of the gins in connection with which it is to be used. I desire it, therefore, to be understood that I reserve the right to any such changes as come fairly within the scope of 20 the invention and which may be resorted to without departing from the spirit or sacrificing the efficiency of the same.
- Having thus described my invention, I claim—
- 25 1. A roll-board for cotton-gins, consisting of a plurality of fingers pivotally mounted adjacent to each other, and spring means for forcing the free ends of said fingers in the direction of the saws.
- 30 2. A roll-board for cotton-gins, including a plurality of pivotally-mounted fingers having

curved surfaces, in combination with springs disposed near the pivoted ends of the fingers and forcing the free ends of the latter in the direction of the saws, and means for obstructing the outward movement of the free ends of said fingers beyond a certain predetermined limit in the direction of the saws. 35

3. In a device of the class described, a casing, a plurality of curved-faced and flat-sided fingers mounted pivotally in said casing adjacent to and movable independently of each other, said fingers having sockets near the pivoted ends thereof, springs seated in said sockets and bearing against a cross-bar of the casing to force the free ends of the fingers in an outward direction, and a cross-bar forming a part of the casing, to intercept and limit the outward movement of the free ends of said fingers. 40

4. A roll-board for gins, including a plurality of pivotally-mounted fingers and means for yieldingly supporting the free ends of said fingers, the latter coöperating to form, when in normal position, a smooth curved surface. 45

In testimony that I claim the foregoing as my own I have hereto affixed my signature in the presence of two witnesses.

FRANCIS L. COWAN.
